DISPENSING PACKAGE FOR RAZOR BLADES

Robert A. Jolie, Marlboro, Mass., assignor to F. J. Kirk Molding Co., Inc., Clinton, Mass., a corporation of Massachusetts

Application August 21, 1948, Serial No. 45,523

2 Claims. (Cl. 206—16)

1

The present invention relates to improvements in dispensing packages, and more particularly to a dispensing package which is particularly adapted to contain razor blades of the type employed with the so-called safety razor.

It is a primary object of the present invention to provide a razor blade package or container which may be originally filled with a stack of blades at the factory and then sold in retail stores to a purchaser who, thereafter, may employ the container as a refillable razor blade dispenser. Thus, the present invention contemplates that the razor blade user may retain this dispenser within his possession and refill the same with a stack of fresh blades whenever the container is empty.

Another object of this invention is to provide a razor blade container which is designed so that a stack of blades may be readily inserted as a unit into the container and thereafter be safely ejected therefrom one at a time.

A further object of the present invention is to provide such a razor blade package and dispenser unit which is most efficient in operation but which, at the same time, is adapted to be most inexpensively manufactured.

A more specific object of the present invention is to provide a unitary razor blade package and dispenser unit which may be fabricated of plastic material by a molding machine in a single operation, to the end that no hand assembly operations are necessary to complete the unit.

With the above and other objects in view as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 represents a top plan view of the present razor blade package and dispenser unit.

Fig. 2 represents a right-hand end view of the unit disclosed in Fig. 1.

Fig. 3 represents a sectional view of the present unit taken substantially along the line 3—3 of Fig. 1.

Fig. 4 represents, on an enlarged scale, a sectional view of the present unit taken substantially along the line 4—4 of Fig. 1, and illustrating the manner in which the razor blades are removed from the unit.

2

Fig. 5 represents, on a reduced scale, a top plan view of the present unit which is illustrated as containing a stack of razor blades.

Referring particularly to Figs. 1, 2 and 3, the present invention comprises a substantially rectangular shaped frame unit including opposed side members 10 and 11 which are connected together at their end portions by means of opposed end members 12 and 13. Projecting inwardly from each of the side members 10 and 11 is an overhanging flange 14 which is provided at that end portion thereof adjacent to the end member 13 with a downwardly depending tooth element 15. As may be particularly seen in Figs. 1 and 3, the end member 12 is provided with an upstanding abutment element 16.

Suspended between the oppositely opposed end members 12 and 13 are a pair of transversely spaced bridge elements 17, 17, each one of which has one of its end portions anchored upon a respective one of the end members 12 and 13. As may be best seen in Fig. 1, there is disposed between the bridge elements 17, 17 a fulcrum tongue 18 which is secured to the spaced bridge elements 17, 17 by means of transverse webs 19, 19. In this connection, it is to be particularly noted that the webs 19, 19 are located at points which are slightly closer to the end member 12 than they are to the end member 13. Furthermore, by referring to Fig. 3, it is to be understood that each of the bridge elements 17, 17 is shaped in the form of a bow or arc.

It is within the contemplation of the present invention to construct the present unit of a material which is elastic, to the extent that the bridge elements 17, 17 will possess a certain amount of inherent resiliency. In this connection, experience has indicated that if the present unit is fabricated, for example, from a plastic material, such as cellulose acetate, the relatively thin bridge or bow elements 17, 17 will have a yieldability against downward pressure, while the heavy side and end members which form the frame of the present unit, will be substantially rigid.

In use, the present unit is adapted to contain a relatively large number of standard safety razor blades. A stack of such blades may be inserted as a unit into the container through the right-hand end portion thereof, as viewed in Figs. 1 and 4. In order to so insert a stack of blades within the container, it is most convenient for the operator to hold the unit in one hand, while, at the same time, depressing the right-hand end portion of the fulcrum tongue 18 with the thumb.

In this latter connection, it will be readily understood that the fulcrum tongue 18 will remain rigid throughout its entire length, while the right-hand end portion thereof is depressed, for the tongue will pivot relative to the package frame about a transverse axis which passes through the webs 19, 19. With the right-hand end portion of the fulcrum tongue so depressed, the operator may then grasp a stack of razor blades 20 with his other hand and insert them endwise over the upper lip of the end member 13 and beneath each of the flanges 14, 14. As the stack of blades is inserted lengthwise into the unit, they will clear the depressed right-hand end portion of the fulcrum tongue 18 and thereafter, the operator may remove his thumb from the tongue and continue to insert the blade stack into the unit, so that it will be positioned in a manner as is particularly illustrated in Fig. 5.

Since substantially all types of safety razor blades are provided with a longitudinally disposed slot, herein designated by the numeral 21, the present unit is designed so that when a stack of blades is positioned within the unit, the opposite end portions of the fulcrum tongue 18 will be received within the slot, thereby to prevent the sharpened side portions of the razor blades from engaging the side portions 10 and 11 of the container unit. It is to be noted that as the leading edge of the stack of blades 20 being inserted engages the left-hand portion of the tongue 18, to depress the same, the right-hand tongue portion will be swung upwardly into the aligned blade slots 21 to guide the blades centrally of the dispenser, as the insertion of the stack is completed.

It is also to be understood that the inherently resilient bridge members 17, 17 will be flattened downwardly whenever the blades are positioned within the unit and thus, the bridges will function to bias the blades upwardly against the underside portions of the flanges 14, 14. Referring particularly to Fig. 5, it will be understood that with the stack of blades so positioned within the unit, it is impossible for anyone to touch the sharpened side portions of the blades, for they are disposed directly beneath the overhanging flanges 14, 14 and within the confines of the side members 10 and 11.

With the stack of blades positioned in a manner as disclosed in Fig. 5, it is impossible for any of the blades to be jolted, or otherwise inadvertently removed from the package by endwise withdrawal. In this latter connection, it is to be understood that the downwardly depending teeth 15, 15 which are provided on each of the flanges 14, 14, are adapted to engage the right-hand shoulder portions of the razor blades, while the upwardly projecting abutment member 16 engages the left-hand end portions of the blades. Also, each of the opposite end portions of the fulcrum tongue 18 projects upwardly through the blade slots 21, to the end that they would normally engage a respective one of the end portions of the slot 21, in the event that any of the razor blades were to be moved endwise of the unit.

In order to remove a razor blade from the present container, it is merely necessary for the operator to hold the unit in his one hand, while he pushes the thumb of that hand downwardly upon the right-hand end portion of the razor stack and simultaneously urges the upper blade in a left-hand direction in a manner as illustrated in Fig. 4. This action of the operator's thumb will depress the right-hand end portion of the ful-

crum tongue 18 so as to permit the right-hand end portion of the top razor blade to pass over the tongue.

Also, by so depressing the right-hand end portion of the razor blade stack, the right-hand end sections of the bridge pieces 17, 17 will yield downwardly, while the left-hand end portions thereof will urge the left-hand end portions of the razor blades 20 upwardly. Thus, as the operator shifts the upper blade of the stack to the left, this blade will be made to clear the abutment member 16, to the end that a single razor blade will be ejected from the unit. This abutment 16, however, is only spaced slightly below the plane which is defined by the sides of the flanges 14, 14, so that it is impossible for more than one blade to be ejected from the unit at one time. As soon as the operator removes his thumb from the upper surface of the blade stack, the fulcrum tongue 18 will assume its normal position within the razor blade slots 21, while, at the same time, the compressed bridge elements 17, 17 will again tend to form their normal arc, thereby to urge the central portions of the blades upwardly toward the flanges 14, 14.

From the above, it will be apparent that the present invention not only provides a razor blade package or container in which stacks of razor blades may be sold over the counter, but, at the same time, it provides a safe and efficient razor blade dispenser which may be refilled by the user whenever the last blade has been removed from the unit. However, in this latter connection, it should be noted that the present unit is so designed that it may be most economically manufactured, to the end that the user could well afford to discard the container once the original charge of blades has been exhausted. In other words, even though the present container may be readily refilled by the user, it is, at the same time, so inexpensive of manufacture that the razor blade makers could well afford to sell all their razor blades in such packages without appreciably increasing the cost of the blades.

An inspection of Figs. 1, 2 and 3 will show one skilled in the art that the present container unit is particularly adapted to be machine molded in a single operation, for the present unit is provided with absolutely no undercuts and thus, simple dies could be used in its manufacture. Furthermore, once the unit has been formed in a molding machine, no further operations are necessary to complete the unit, with the exception of removing the molding sprue or runner from an outside portion of the unit.

I claim:

1. A dispensing package for razor blades comprising, a substantially rectangular shaped frame having a pair of opposed longitudinally extending side members and a pair of opposed transversely extending end members, a flange extending inwardly from an upper portion of each of said side members thereby to form a channel, a stack of razor blades positioned within said channel, 60 with the under surfaces of said flanges defining a plane which is spaced above a first one of said end members a distance substantially greater than the thickness of at least two blades so as to define between said first end member and said flanges an opening for receiving said stack of blades, a tooth depending downwardly from that end portion of each of said flanges adjacent to said first end member for engaging the end portions of said blades once they have been positioned within the 70 confines of said container thereby to prevent any

retrograde movement of said blades, an abutment member extending upwardly from a second one of said end members so as to be spaced below the plane defined by the under surfaces of said flanges a distance not exceeding the 5 thickness of a single blade thereby to define between said abutment member and said flanges a blade egress opening, and an inherently resilient portion formed integrally with said frame and normally biased toward said plane thereby to 10 urge said stack of blades toward and against the under surfaces of said flanges.

2. A dispensing package for razor blades comprising, a substantially rectangular frame having a pair of opposed longitudinally extending 15 side members and a pair of opposed transversely extending end members, a flange extending inwardly from an upper portion of each of said side members to form a channel open along its middle, a stack of razor blades positioned within 20 said channel, and having aligned slots extending lengthwise of the channel, with the undersurfaces of said flanges spaced above one of said end members a distance greater than the thickness of at least two blades, so as to define an opening 25 for receiving a stack of blades endwise, an abutment member extending upwardly from the other end member and being spaced from the adjacent end portions of said flanges a distance sufficient to just permit the passage of a single 30 razor blade therebetween, and a blade-locking

tongue yieldingly mounted between said side members of the frame and extending longitudinally of said channel so as to be received within the aligned slots of said stack of blades as positioned within said channel, said locking tongue being compressible at one end to permit a stack of blades to be inserted within the package through the opening at one end of said channel, as well as being compressible at its opposite end to permit a single blade to be ejected from the package through the opening at the opposite end of said channel.
